[57] CLAIM

The ornamental design for a hanger for garment tops or the like, as shown and described.

DESCRIPTION

FIG. 1 is a front elevational view of a hanger for garment tops or the like showing our new design, the rear being a mirror image;

FIG. 2 is a bottom plan view thereof;

FIG. 3 is a top plan view thereof; and

FIG. 4 is a right side elevational view thereof, the left side being substantially identical.

Fig. 1.

Fig. 2.

Fig. 3.

Fig. 4.
